(57) **CLAIM**

The ornamental design for an automobile nose or replica thereof, as shown and described.

DESCRIPTION

FIG. 1 is a front, left perspective view of an embodiment of an automobile nose or replica thereof in accordance with the present design;

FIG. 2 is a front elevation view thereof;

FIG. 3 is a left elevation view thereof;

FIG. 4 is a right elevation view thereof;

FIG. 5 is a top plan view thereof;

FIG. 6 is a rear, left perspective view thereof; and,

FIG. 7 is a rear elevation view thereof.

Portions of the automobile nose or replica thereof shown in dot-dash lines depict an unclaimed boundary between claimed and unclaimed portions of the automobile nose or replica thereof. Portions of the automobile nose or replica thereof shown in evenly spaced broken lines depict environmental structures that form no part of the claimed design.
